TOY AMUSEMENT RIDE

Frank D. McDonald, Los Angeles, Calif., assignor to
Wen-Mac Corporation, a corporation of California

Filed June 18, 1963, Ser. No. 75,409

Term of patent 3½ years

(Cl. D34—15)

The single figure is a perspective view of a toy amusement ride, showing my new design.

The sides opposite the sides shown are substantially the same as those shown.

I claim:

The ornamental design for a toy amusement ride, substantially as shown and described.
